E. BURNET.
BOTTLE AND LIKE CLOSING DEVICE.
APPLICATION FILED FEB. 6, 1922.

Patented Oct. 10, 1922.

UNITED STATES PATENT OFFICE.

EDWARD BURNET, OF LONDON, ENGLAND.

BOTTLE AND LIKE CLOSING DEVICE.

Application filed February 6, 1922. Serial No. 534,614.

To all whom it may concern:

Be it known that I, EDWARD BURNET, a subject of the King of Great Britain, residing in London, England, have invented 5 certain new and useful Improvements in Bottles and like Closing Devices, of which the following is a specification.

My invention relates to improvements in bottle and like closing devices that form 10 substantially air and fluid-tight closures, and comprises a metallic cover or cap containing an elastic packing or washer that is pressed and retained against the mouth on the neck of the bottle or other receptacle. It has for its object to provide a closing device or stopper that will permit of the withdrawal of the contents of a bottle 15 without removal of the stopper, which is neat in appearance and hygienic.

20 The cover or cap of the improved stopper consists of an end disc of aluminium or other suitable metal, having a central aperture and a depending flange or skirt, the diameters of the aperture in the end or 25 top of the cap and of the lumen of the bottle neck being preferably made the same. Interposed between the inner or lower face of the top of the cap and the mouth of the bottle is a packing piece or washer 30 which consists of a comparatively thick disc of spongiouse rubber between two thin layers of ordinary impermeable rubber. The washer and cap of the stopper may either remain separate or unattached, or the 35 washer may be secured to the inside of the cap by means of an appropriate adhesive agent.

When a stopper is placed on the mouth of the bottle it is kept pressed tightly against 40 it while its skirt is made to fit around the neck of the bottle by applying pressure, by means of any suitable appliance, to the wall of the skirt. Alternatively, the skirt may be formed with a screwthread for engagement with a corresponding thread moulded on the bottle neck.

The improved stopper is particularly suited for use with bottles containing vaccine, which can be extracted from inside 45 the bottle by puncturing, with the needle of

a hypodermic syringe, the portion of the washer exposed within the aperture of the cap, the spongiouse disc faced top and bottom with ordinary rubber ensuring that all punctures will be self-closing on the withdrawal of the needle. 55

The invention will be further described with reference to the accompanying drawings, in which Fig. 1 is a section of a portion of a bottle, drawn to an enlarged scale 60 and having the improved stopper in its preferred form applied to it. Fig. 2 is a similar view showing the stopper in another form and screwed on the neck of the bottle, and Fig. 3 is a section showing the cap 65 and the associated washer before it is compressed by pressing the cap on to the neck of the bottle. In the several figures corresponding parts are indicated by the same letters. 70

In the drawings *a* denotes the upper portion of a bottle, *b* is a metallic cover or cap having a central aperture *b'* and a flange or skirt *b*². Nested in the flanged cap is an elastic packing or washer consisting, as 75 depicted in Fig. 3, of a layer or disc of spongiouse rubber *c* interposed between two discs *c'*, *c*² of ordinary impermeable rubber.

In Fig. 1 the lower edge *b*³ of the skirt *b*² has been bent by spinning and made to fit 80 under the lip or rim *a'* of the bottle.

In Fig. 2 the skirt *b*⁴ is formed with a screwthread and is engaged with screwthreads *a*² on the bottle neck.

Having thus described the nature of the 85 said invention and the best means I know of carrying the same into practical effect, I claim:—

1. A bottle stopper comprising in combination a metallic cap consisting of a flat top 90 portion having a central aperture and a depending skirt embracing the bottle neck, and an elastic washer housed within the cap and interposed between the neck of the bottle and the underside of the cap top, said 95 washer consisting of an upper and a lower disc of impermeable rubber and a disc of spongiouse rubber interposed between the said upper and lower discs.

2. A bottle stopper comprising in com- 100

bination a metallic cap consisting of a flat top portion having a central aperture and a depending skirt embracing the bottle neck, and an elastic washer housed within the cap
5 and interposed between the neck of the bottle and the under side of the cap top, said washer consisting of an upper and a lower disc of impermeable rubber and a

disc of spongiose rubber interposed between the said upper and lower discs, the edge 10 of the said depending skirt being spun around the neck of the bottle.

In testimony whereof I have signed my name to this specification.

EDWARD BURNET.
